UNITED STATES PATENT OFFICE.

EBENEZER A. BOWERS, OF LUCERNE, MISSOURI.

FOOT-BLOCKING FOR GUARD-RAILS.

SPECIFICATION forming part of Letters Patent No. 732,511, dated June 30, 1903.

Application filed April 20, 1903. Serial No. 153,380. (No model.)

To all whom it may concern:

Be it known that I, EBENEZER A. BOWERS, a citizen of the United States, residing at Lucerne, in the county of Putnam and State 5 of Missouri, have invented certain new and useful Improvements in Foot-Blocking for Guard-Rails, of which the following is a specification.

This invention relates to foot-blocking for 10 guard-rails, and has for its object to produce a foot-block for use between a guard-rail and a track-rail which is of simple, strong, durable, and inexpensive construction and which largely reduces chance of death or 15 serious injury by eliminating the possibility of catching one's foot between the guard and track rails in such a manner that it cannot be quickly or easily withdrawn.

To this end the invention consists in certain 20 novel and peculiar features of construction and combinations of parts, as hereinafter described and claimed, and in order that it may be fully understood reference is to be had to the accompanying drawings, in which—

25 Figure 1 is a top plan view of a track-rail and a guard-rail with a foot-block embodying my invention interposed and secured between them. Fig. 2 is an enlarged cross-section taken on the line II II of Fig. 1. Fig. 3 is a 30 perspective view showing a portion of the rail and the contiguous ends of the guard-rail and foot-block.

In the said drawings, 1 designates the 35 track-rail of an ordinary railway system or of a street-railway system, and 2 the guard-rail arranged contiguous to the main rail opposite the frog, (not shown,) the opposite ends of the guard-rail being turned or curved inward in the usual manner, as at 3.

40 4 designates the foot-block, fitting snugly between the rail 1 and guard-rail 2 and projecting beyond the ends of the latter, said projecting ends diverging to the opposite sides of the block, as at 5, and at the inner corners of the block it is provided with enlargements or shoulders 6, bearing squarely against the ends of the guard-rail. The block fits 45 snugly between the base and head flanges of

the rails, as well as against the webs thereof, and in its upper side is channeled or grooved, 50 as at 7, this channel or groove being sufficiently deep at its shallowest point to accommodate the wheel-flanges. At suitable distances from the ends of the block this groove 7 begins to gradually deepen and increases in 55 depth to its ends, as at 8, leaving the block at each end of U shape in cross-section, the upwardly-projecting arms of the U having their inner sides approximately flush with the inner sides of the heads of the rails, so 60 as to eliminate any possibility of one's foot being caught and wedged tightly between the rails.

The foot-block is secured reliably between 65 and under the heads of the rails by means of bolts 9, extending through the rails and the foot-block, the inner ends of the bolts being engaged by retaining-nuts 10 of the usual or any preferred construction.

From the foregoing it will be apparent that 70 the provision of a solid foot-block of greater length than and having shoulders bearing against the ends of the guard-rail and united to the latter and to the track-rail by cross-bolts produces an exceedingly strong and durable 75 structure and that the peculiar shape of the foot-block and its relation to the rails practically eliminate the chance of a switchman or other person getting his foot caught in such a manner that he cannot readily disengage it.

Having thus described the invention, what I claim as new, and desire to secure by Letters Patent, is—

1. In foot-blocking for guard-rails, the combination of a track-rail, a guard-rail inward thereof, and a foot-block fitting between said rails, and having inwardly-projecting shoulders at its opposite ends engaging the ends of the guard-rail. 85

2. In foot-blocking for guard-rails, the combination of a track-rail, a guard-rail inward thereof, and a foot-block fitting between said rails, and having inwardly-projecting shoulders at its opposite ends engaging the ends 95 of the guard-rail, and provided with a groove

or channel in its upper sides corresponding in width to the distance between the inner sides of the rails, and increasing gradually in depth from suitable points to its ends.

5 3. A foot-block which increases in width gradually at its ends, is provided at its inner corners with inwardly-projecting shoulders, and is provided in its upper side with a groove

or channel which increases in width and in depth at its ends.

In testimony whereof I affix my signature in the presence of two witnesses.

EBENEZER A. BOWERS.
